UNITED STATES PATENT OFFICE.

JAMES L. EADIE AND CHARLES N. BOSTON, OF HARTLAND, MAINE.

ALARM ATTACHMENT FOR CARDING-MACHINES.

SPECIFICATION forming part of Letters Patent No. 683,596, dated October 1, 1901.

Application filed September 26, 1900. Serial No. 31,171. (No model.)

To all whom it may concern:

Be it known that we, JAMES L. EADIE and CHARLES N. BOSTON, citizens of the United States, residing at Hartland, in the county of 5 Somerset and State of Maine, have invented new and useful Improvements in Alarm Attachments for Carding-Machines, of which the following is a specification.

This invention relates to new and useful 10 improvements in alarm attachments for carding-machines; and its primary object is to provide a simple and inexpensive device of this character which will sound an alarm when the wool within the feed is nearly exhausted or when the roving breaks.

The device is especially adapted for use upon Bramwell and Bates feeds.

To these ends the invention consists in providing a bracket to which are pivoted strips 20 each of which is secured to a wire of an electric circuit. Means are provided whereby these strips are thrown into contact with each other, thereby forming a circuit and sounding a suitable alarm which will indicate the 25 condition of the feed. Different means are necessary to operate these contact-strips, the character thereof being governed by the form of machine to which the alarm is applied.

In the accompanying drawings we have 30 shown the preferred form of our invention, which is adapted to be attached to an ordinary Bates feed.

Figure 1 is a perspective view of a portion of a Bates feed, showing the alarm attachment applied thereto. Fig. 2 is a front elevation of said attachment. Fig. 3 is a detail view of the bracket and the contact-strips thereon. Figs. 4 and 5 are detail views of 35 said strips detached. Fig. 6 is a face view 40 of a modified form of attachment. Fig. 7 is an edge view thereof.

Referring to the drawings by numerals of reference, 1 is a side plate which is adapted to be secured to the standard 2 of a Bates 45 feed and is provided with a stud 3 extending laterally therefrom. Loosely mounted upon this stud is a spider having collar 4 and which is prevented from moving laterally upon said stud by means of sleeves 5, as shown.

50 An arm 6 projects downward from the collar and is curved slightly at the end thereof, as at 7, said end being arranged slightly above

the feed-aprons 8 of the machine at a point in front of a trumpet 9, of ordinary construction, arranged at a point adjacent to the distributing-rolls 10. The curved end 7 of the arm normally contacts with the roving fed into the trumpet 9. Arms 11 and 12 extend upward in different directions from the collar 4, and slidably mounted upon the left-hand arm 11 is a weight 13, which is adapted to be held in adjusted position by means of a set-screw 14, extending therethrough and normally binding upon said arm. The right-hand arm 12 extends laterally to a point below and in the path of a lower strip 15, having a spoon-shaped end 16 thereto. This strip is pivoted to a bracket 17, secured to the feed-carrier of the machine, and is adapted to be thrown upward into contact with a small pendant upper strip 18, also pivoted to the base 70 17. By pivoting this strip the same may be adjusted so as to regulate the amount of movement of the arm 12 necessary in order to bring the same into contact with said strip. 75 This strip is preferably struck up from a blank of suitable metal and is secured to one end of a wire 19 of an electric circuit, the strip 15 being secured to a second wire 20 thereof. These wires may be connected to a bell or 80 other suitable alarm which is adapted to be sounded when the two strips are thrown into contact with each other. The roving when fed through the trumpet will prevent the arm 6 from swinging laterally in the direction of 85 the bracket 17 under pressure of the weight 13. When, however, the roving breaks, the arm 6 will promptly swing laterally and cause the arm 12 to bear upon the enlarged portion 16 of strip 15 and force it against the end of 90 the strip 18.

Pins or studs 21 are arranged upon the face of the plate 5 and are adapted to limit the movement of the spider having the collar and the arms projecting therefrom.

95 It will be understood that by adjusting the strip 18 upon its pivot the amount of motion necessary before the strips 15 and 18 are placed in contact with each other is readily regulated.

100 The device shown in Figs. 6 and 7 of the drawings is adapted to be employed in lieu of that portion of the apparatus illustrated in Fig. 3. This modified form comprises

strips 22 and 23, which are mounted in a manner similar to that before described in connection with the strips 15 and 18 and which when thrown into contact with each other complete the circuit through wires 24.

Having thus described the invention, what is claimed, and desired to be secured by Letters Patent, is—

An alarm attachment for carding-machines comprising a side plate, provided with a laterally-extending stud, and stop-pins, a spider having a collar whereby it is loosely mounted on the stud, a depending arm, having a curved end, a left-hand arm, and a right-hand arm,

a counterbalance-weight secured to the left-hand arm, a bracket, a lower contact-strip pivoted to the bracket and against which the right-hand arm is adapted to impinge, and an upper contact-arm adjustably secured to the bracket.

In testimony whereof we affix our signatures in presence of two witnesses.

JAMES L. EADIE.
CHARLES N. BOSTON.
